US00D626422S

(12) **United States Design Patent**
Lloyd

(10) **Patent No.:** **US D626,422 S**
(45) **Date of Patent:** **** Nov. 2, 2010**

(54) **FRAGRANCE BOTTLE**

- (75) Inventor: **Douglas Lloyd**, New York, NY (US)
- (73) Assignee: **ELC Management LLC**, New York, NY (US)
- (**) Term: **14 Years**
- (21) Appl. No.: **29/328,121**
- (22) Filed: **Nov. 19, 2008**

Related U.S. Application Data

(57) **CLAIM**

The ornamental design for a fragrance bottle, substantially as shown and described.

DESCRIPTION

FIG. 1 is a top, front, right side perspective view of a fragrance bottle showing my new design;

FIG. 2 is a front elevational view thereof, a rear elevational view being a mirror image thereof;

FIG. 3 is a right side elevational view thereof, a left side elevational view being a mirror image thereof;

FIG. 4 is a top plan view thereof; and,

FIG. 5 is a bottom plan view thereof.
